MATTRESS REINFORCING DEVICE

Max Rosberger, Newark, N. J.

Application June 5, 1948, Serial No. 31,251

5 Claims. (Cl. 5—317)

1

This invention relates to improvements in mattresses and coil spring sections thereof. Mattresses and coil spring sections are initially manufactured with spring and other yielding devices which initially provide a uniform cross-sectional area.

In use, however, the mattress and coil spring tend to sag at the center, where the greatest weight is usually concentrated, so that, in time, the sagging effect becomes very pronounced and impairs the usefulness of the mattress and coil spring.

Pursuant to the instant invention, an expansion device is provided, which is adapted to be secured to or formed integral with the mattress and/or coil spring section, providing ready means for compensating for the sagging thereof, in a manner which will become apparent from the description hereinafter.

These and other advantageous objects, which will appear from the drawings, and from the description hereinafter, are accomplished by the structure of my invention, of which embodiments are illustrated in the drawings. It will be apparent, from a consideration of said drawings, and the following description, that the invention may be embodied in other forms suggested thereby, and such other forms as come within the scope of the appended claims are to be considered within the scope and purview of the instant invention.

In the drawings:

Fig. 1 is a side elevational view of a mattress provided with an expansion device pursuant to my invention.

Fig. 2 is a side elevational view of a coil spring having an expansion device embodying my invention integrally incorporated in the medial section thereof.

Fig. 3 is a perspective view of a coil spring having an expansion device embodying my invention secured to the medial portion of the top thereof.

Fig. 4 is a perspective view of one form of expansion device embodying my invention.

Fig. 5 is a vertical, longitudinal, sectional view of another form thereof.

Fig. 6 is a top plan view, partly fragmentary, of a further form thereof.

Figs. 7 and 8 are perspective views of other forms thereof.

Fig. 9 is an enlarged vertical, elevational view, taken on line 9—9 of Fig. 6, and

Fig. 10 is a similar view, taken on line 10—10 of Fig. 6.

As shown in the drawings, the expansion device

2

of my invention preferably comprises a flexible sheet member with means—manually operable—to contract the expansion device marginally to arch the same and thereby provide the required expansion for the mattress or coil spring.

In the form shown in Fig. 8, the expansion device 20 comprises a flexible sheet member 21 which may be arched, as noted in said figure, upon the operation of the contracting member 25.

In the form shown in Fig. 7, the expansion device 30 comprises flexible sheet members 21, 21', marginally secured together or within the marginal members 24, 24', to which the contracting member 25 is secured. By this arrangement, it will be apparent that upon the operation of the contracting member, the marginal edges 24, 24' will be brought together to arch the sheets 21, 21' and thereby provide an expansion device for the purpose above set forth. The expansion device 20 of Fig. 8 is provided with a contracting member 25 which may be of any desired or convenient construction and is manually operable, as shown in Fig. 8, illustrating one of many possible variations of said device, comprising a manually rotatable turnbuckle 27 connected to the marginal strips 24, 24'.

In the form shown in Fig. 1, the mattress M is provided with a compartment 26 which may be incorporated in said mattress in the initial manufacture thereof or may be secured to the underside thereof medially. Said compartment may be closed at the ends thereof by a flap or flap members, having any desired or convenient zipper arrangement. The turnbuckle 27 may be connected to the marginal plates by springs 28, or the like, if so desired. The flexible sheet members 21, 21' may be provided with springs (29, Fig. 7) underlying the same and secured at their ends to the strips 24, 24'. If desired, the spring members, instead of being secured to said marginal plates, might be of the coil type, and may be positioned intermediate the sheets 21, 21' and terminally secured thereto. The function of these springs is to reinforce the sheets 21, 21', and absorb forces exerted.

In the form shown in Fig. 2, the expansion device 30 is incorporated in the coil spring C medially thereof, in initial manufacture, by securing the same to coil units medially in any desired or convenient manner.

In the form shown in Fig. 3, the expansion device 20 is secured to the top of the coil spring C, medially, by bolts 32 or the like.

In the form shown in Fig. 4, the contracting device 35, like the contracting device 25 of Figs. 7

and 8, is secured to the marginal strips 24, 24' (shown in dotted lines). Said contracting device, as shown in said figure, comprises a threaded shaft 36 journalled in bearings 31, 31', fixed to tubes 38, the latter defining, with the rod 39 to which said bars are connected, one half of a frame secured to the marginal strips 24, 24'. The other half of said frame comprises the rod 41 and the bars 46, 46' connected thereto and telescopically received in the tubes 38. A crank 42 is keyed to the threaded shaft 36, which is engaged by internally threaded nut members 43, 43', 44, 44'. It will be understood that the internally threaded members and corresponding portions of shaft 36, are provided with suitable left and right threads, so that on rotation of the shaft 36 in one direction, the nut members 43, 43' and 44, 44' will be drawn together to cause the frame, and thereby the marginal strips 24, 24' of the expansion device, to contract. This is attained in the device shown in Fig. 4 by connecting the nut members to the rods 39, 41 of the frame by links 45, 46, 45', 46', 47, 48, 47', 48'.

It will be apparent that in the use of the structure shown in Fig. 4, just described, it is simply necessary to rotate the crank in one direction to cause the contraction of the strips 24, 24' and thereby cause the flexible sheet members 21, 21' to expand into convexo-convex form.

A similar arrangement is shown in Fig. 5, wherein bearings 50, 50' are fixed to the sheet 21', and a shaft 51 is journalled in said bearings and has fixed to the outer end thereof a crank 52. Gears 53, 53' are fixed to the shaft 51 in spaced relation and mesh with gears 54, 54' rotatably disposed on standards 55, 55', said gears having keyed thereto threaded members 56, 56' engaging the internally threaded sockets 51, 51' fixed to the sheet member 21.

In the arrangement shown in Figs. 6, 9 and 10 a shaft 60 is rotatably and slidably journalled in standards 61, 61', in telescopic engagement with posts 62, 62' fixed to the sheet member 21', spring members 63, 63' being interposed between the top ends of the posts and the lower end of the standards and normally urging the latter away from the former. Reels 64, 64' are slidably keyed to the shaft 60 and have cables 65, 65' entrained thereover, said cables being connected at opposite ends to said reels and to the marginal strips 24, 24'. A clutch element 66 is keyed to shaft 60 and connected to one end of spring 67 which is fixed at the other end to the reel 64, said spring normally urging the clutch element 66 into engagement with the clutch head 68 of the standard 61 to lock the shaft 60 against rotation. The clutch elements 66 and 68 are preferably provided with mating serrations or other clutch faces. The reels 64, 64' are provided with internal non-circular apertures conforming to the cross-sectional configuration of the shaft 60 so as to slidably key said reels to the shaft. The clutch element 66 is keyed to said shaft, the shaft freely passing through the clutch plate 68 of the standard 61 and through the standard 61'. By this arrangement, on movement of the crank 69 of shaft 60, in the direction of the arrow D of Fig. 6, the clutch element 66 will be moved away from the clutch head 68, permitting the crank to be rotated to contract the strips 24, 24'. Upon release of the crank 69, the spring 67 will urge the clutch arrangement 66 into clutch engagement with the head 68 of the standard 61, automatically locking the parts against accidental displacement.

It will be apparent to those skilled in the art

to which the instant invention relates, that modifications of the structure shown in the drawings and described herein, may be made within the scope and purview of the invention, as defined in the appended claims. Thus, for example, flat springs, such as band or cable springs, may be substituted for the "no sag" style of spring 29 shown in Fig. 7.

The invention herein disclosed is adapted for use in connection with upholstered furniture, studio sofa beds, love seats, auto seats, and, in fact, for all articles used for seating purposes, having upholstered materials, springs or other yieldable portions.

Having thus described my invention, what I claim as new and desire to secure by Letters Patent is:

1. A device to compensate for the medial sagging of an article of furniture, comprising a resilient, flexible sheet member having spaced parallel edges, strips secured to said edges, spring members having outer ends secured to said strips, and an expansion and contraction device secured to the inner ends of said springs connecting the same and operable to expand and contract the sheet member.

2. A device to compensate for the medial contraction and sagging of an article of furniture, comprising a pair of flexible, resilient sheet members, and means engaging the sheet members to hold them together, said sheet members having spaced parallel edges, springs secured at their outer ends to said edges, a rectangular expansion frame secured to the other ends of said springs, and manually operable means in said expansion frame to expand and contract the frame and thereby, through said springs, to expand and contract the sheet members in convexo-convex form.

3. A device to compensate for the medial contraction and sagging of an article of furniture, comprising a flexible, resilient sheet member having spaced marginal edges, strips secured to said edges, a manually rotatable turnbuckle, and means connecting the turnbuckle to the strips whereby, on rotation of the turnbuckle in one direction, the marginal edges of the sheet member will be drawn together so that the sheet member will define an arch in cross-section, and, on rotation of the turnbuckle in the other direction, the marginal edges of the sheet will move apart to define an arch of lesser radius.

4. A device to compensate for the medial contraction and sagging of an article of furniture, comprising a resilient flexible sheet member having spaced marginal edges, strips secured to said edges, manually rotatable means and means connecting the first mentioned means to the strips whereby, on rotation of the first mentioned means in one direction, the marginal edges of the sheet member will be drawn toward each other so that the sheet member will define an arch in cross-section, and, on rotation of the first mentioned means in the other direction, the marginal edges of the sheet will move apart to define an arch of lesser radius.

5. A device to compensate for the medial contraction and sagging of an article of furniture, comprising a resilient flexible sheet member having spaced marginal edges, manually rotatable means and means connecting the first mentioned means to the marginal edges of the sheet member, whereby, on rotation of the first mentioned means in one direction, the marginal edges of the sheet member will be drawn toward each

2,545,810

5

other so that the sheet member will define an arch in cross-section, and, on rotation of the first mentioned means in the other direction, the marginal edges of the sheet will move apart to define an arch of lesser radius.

MAX ROSBERGER.
